PUMP, COMPRESSOR, MOTOR, OR THE LIKE

Oskar Birger Ljungdahl, Stockholm, Sweden

Application May 6, 1941, Serial No. 392,143
In Sweden May 22, 1940

6 Claims. (Cl. 103—130)

The present invention relates to a pump, compressor, motor or the like but is described hereinafter substantially arranged as a pump or compressor. The invention is substantially characterized by a screw-thread eccentrically and rotatably mounted on a shaft in a pump housing and a corresponding screw-thread provided along the inner wall of the pump housing, the screw-threads being so arranged relatively to one another that during the rotation of the shaft an entire engagement and sealing between the threads is always established along a rotating broken line, the diametrically located portions of the threads tightening against one another only with their side-top portions.

Two embodiments of the device according to the invention are illustrated on the accompanying drawings, in which

Fig. 1 is a longitudinal section of one embodiment,

Fig. 2 is a longitudinal section of the second embodiment,

Fig. 3 shows a section on the broken line III—III in Fig. 1, and

Fig. 4 shows a detail.

Referring to the drawings, reference character 2 designates a pump housing, to the inside of which a cylindric sleeve 4 is secured by means of screws 3, said sleeve being provided with an internal thread 5. Through the cylindric sleeve there extends a shaft 6, on which a sleeve 7a with a screw 7 is eccentrically mounted, said sleeve 7a having a thread 7b corresponding to the thread 5. The shaft 6 has an eccentric portion 8, on which part of a sphere 9 is centrally mounted, said sphere being interposed between a sleeve 11, mounted on the shaft 6 and secured to the same by means of a screw 10, and a sleeve 13 threaded on to the shaft 6 and secured to the same by means of a screw 12. In order to equalize the running of the pump the sleeves 11 and 13 are formed as fly weights 11a and 13a on that side which is remote from the eccentric 8, as will be seen from Figs. 1 and 2. On the sphere 9 there is slidably mounted a collar surrounding the same, one half 15 of which abuts against a shoulder 14 formed on the sleeve 7a, while the other half 16 abuts against the first mentioned half. The collar half 16 is secured to the sleeve 7a by means of screws 17. Since the diameter of the thread 7b is smaller than that of the thread 5, the pitch of every point of the thread 7b will be greater than that of the corresponding point of the thread 5. The sphere 9 and the collar surrounding the same allow a certain inclination of the

axis of the sleeve 7a relatively to the shaft 6, whereby the threads 5 and 7b will substantially engage one another. Reference numeral 18 denotes a sealing ring between the pump housing 2 and the sleeve 4, said ring being maintained in its position by means of a ring 19 secured to the sleeve 4 by means of screws 20. At the opposite end (the intake end) of the pump housing a sealing ring 21 is also secured between the pump housing 2 and the sleeve 4 by means of a ring 22, which is secured to the sleeve by means of screws 23.

During the rotation of the shaft 6 there will always be an entire engagement between the two threads along a broken line, the contour of which is the same as that of the two threads (see Figs. 1 and 2) and the position of which depends on the position of the eccentric 8.

At the pressure side of the pump housing the cover 24 is secured by means of nuts and bolts 25. In the cover there is provided a ball-bearing 26 carrying the shaft 6. At the suction side of the pump housing there is also a cover 27 secured by means of nuts and bolts 28. In the cover there is provided a ball bearing 29 carrying the shaft 6. Reference character 30 indicates an oil casing provided at each ball bearing, to which casing oil is supplied through the nipple 31. Reference character 32 denotes sealing rings for the oil casing.

The fluid enters the suction chamber 34a through the pipe 33 and a channel 34 in the cover 27 and is forced out from the pressure chamber 35a to the pipe 36 through a channel 35 in the cover 24. The shaft 6 is driven by means of a belt pulley 37. Reference character 38 denotes a supporting plate.

In Fig. 2, which shows an embodiment intended to operate as a compressor, the same reference characters are used for the same elements as in Fig. 1.

In this case, and when oil is used as sealing and lubricating means, a blade wheel 40 rigidly secured to the sleeve 11 in the chamber 35a separates the oil and returns the same to the chamber 34a through a pipe 41.

Owing to the higher pressure in the chamber 35a the oil is sprayed through a nozzle 42 into the chamber 34a against a blade wheel 43 rigidly secured to the shaft 6 so that the oil is finely divided to an oil mist which is mixed with the gas, which is of great importance for the capacity of the compressor.

Having now described my invention, what I

claim as new and desire to secure by Letters Patent is:

1. A machine of the character described, comprising a pump housing having an oil containing suction chamber located at one end and having a gas inlet and having an oil containing pressure chamber located at the opposite end and having a gas outlet, a rotatable shaft having a portion arranged in said housing, a screw thread eccentrically and rotatably mounted on the portion of the shaft in the pump housing, a corresponding screw thread provided in the pump housing the screw threads being so arranged relatively to one another that during the rotation of the shaft a pumping action is effected and an entire engagement and sealing between the threads is always established along a rotating broken line, the diametrically located portions of the threads tightening against one another only with their side-top portions, a pipe connecting the pressure chamber with the suction chamber for conveying lubricating oil from one chamber to the other, a first blade wheel provided on the shaft and located in the pressure chamber and arranged to separate oil from the gas as the mixture of oil and gas leaves the screw threads, the oil being forced by the higher pressure through said pipe to the suction chamber and a second blade wheel on said shaft and located in the suction chamber at a position to receive the oil forced through said pipe, whereby the second blade wheel finely divides the oil so that it mixes with the gas.

2. A machine of the character described, comprising a pump housing having an oil containing suction chamber having a gas inlet at one end and having an oil containing pressure chamber having a gas outlet at the other end, a rotatable shaft having a portion arranged in said housing, a screw thread eccentrically and rotatably mounted on the portion of the shaft in the pump housing, a corresponding screw thread provided in the pump housing, the screw-threads being so arranged relatively to one another that during the rotation of the shaft a pumping action is effected and an entire engagement and sealing between the threads is always established along a rotating broken line, the diametrically located portions of the threads tightening against one another only with their top-side portions, a pipe connecting the pressure chamber with the suction chamber for conveying lubricating oil from one chamber to the other, a first blade wheel provided on said shaft and located in the pressure chamber and arranged to separate oil from the gas as the mixture of oil and gas leaves the screw threads, the oil being forced by the higher pressure through said pipe to the suction chamber, a second blade wheel on said shaft arranged in the suction chamber at a position to receive the oil forced through said pipe, whereby the second blade wheel finely divides the oil so that it mixes with the gas, and a nozzle at the discharge end of said pipe to spray the oil against the second blade wheel.

3. In a machine of the character described, a pump housing having an annular wall and having an inlet and an outlet, a rotatable drive shaft having a portion arranged in the pump housing, a screw thread eccentrically and rotatably mounted on the portion of the shaft which is arranged in the pump housing, a sleeve removably mounted in the pump housing and having its periphery engaging the inner surface of said an-

nular wall, means securing the sleeve to said wall, annular sealing means arranged at the ends of the sleeve to prevent the passage of fluid between the sleeve and wall, a screw thread provided on the inner surface of the sleeve and corresponding to the screw thread on the shaft, the screw threads being so arranged relatively to one another that during the rotation of the shaft a pumping action is effected and an entire engagement and sealing between the threads is always established along a rotating broken line, the diametrically located portions of the threads sealing against one another only with their side-top portions.

4. A machine of the character described, comprising a pump housing, a rotatable drive shaft having a portion arranged in the housing, a screw thread eccentrically and rotatably mounted on the portion of the shaft which is within the pump housing, a corresponding screw thread fixedly secured in the pump housing and engaging the first mentioned screw thread in such manner as to effect pumping action when the shaft is rotated, a pressure chamber in the housing at one end of the screw threads for receiving lubricating oil and having an outlet, a suction chamber in the housing at the opposite ends of the screw threads and also having an inlet, a blade wheel rotatable with the shaft and arranged in the pressure chamber for forcing lubricating oil centrifugally, a pipe for leading oil so forced from the pressure chamber and for spraying it into the suction chamber, and a second blade wheel rotatable with the shaft and arranged in the suction chamber to receive the oil so sprayed and to mix it with gas that is to be compressed by the screw threads.

5. A machine of the character described, comprising a pump housing having an inlet and an outlet opposed to each other, a rotatable shaft having a portion extending into the pump housing, said portion including a cylindrical part arranged eccentrically relatively to the axis of the shaft, counter-balance weights fixed to the shaft adjacent to said cylindrical part, a screw thread rotatably mounted on said cylindrical part, a corresponding screw thread fixedly arranged in the pump housing and engaging the first mentioned screw thread, the screw threads being so arranged relatively to one another that during the rotation of the shaft, a pumping action is effected and an entire engagement and sealing between the threads is always established along a rotating broken line, the diametrically located portions of the threads sealing against one another only with their side-top portions.

6. In a machine of the character described, a pump housing having an inlet and an outlet, a rotatable shaft having a portion arranged in said housing and provided with an eccentrically mounted substantially spherical part, a screw thread surrounding said part and having a substantially spherical surface slidably engaging said substantially spherical part and a corresponding screw thread fixedly arranged in the pump housing and engaging the first mentioned screw thread, the screw threads being so arranged relatively to one another that during the rotation of the shaft a pumping action is effected and an entire engagement and sealing between the threads is always established along a rotating broken line.

OSKAR BIRGER LJUNGDAHL.
